UNITED STATES PATENT OFFICE.

PAUL B. MURPHY, OF NYACK, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed August 28, 1920. Serial No. 406,584.

To all whom it may concern:

Be it known that I, PAUL B. MURPHY, a citizen of the United States of America, residing at Nyack, in the county of Rockland, 5 State of New York, have invented certain new and useful Improvements in Signaling Systems, of which the following is a full, clear, concise, and exact description.

This invention relates to signaling systems and more particularly to methods of and means for signaling to distant stations by modified carrier waves.

It has been proposed in telephone toll line signaling to employ two sources of different 15 frequency alternating currents and to cause these currents to be alternately applied to the line in regular sequence. At the receiving station two circuits tuned respectively to the frequencies of these two currents are 20 arranged to control the windings of a biased polarized relay. While these currents are being applied alternately to the line, the polarized relay armature is kept in motion and thus causes the local ringing relay bell or 25 signal lamp to be energized. When application of these two currents ceases the signal element deenergizes.

A particular advantage of the use of this 30 system for telephony is that the frequencies of these ringing currents may be made such that they will fall within the speech frequency range for which most efficient transmission may be had. They are, therefore, readily handled by the ordinary telephonic 35 transmission line elements. Moreover, the alternate frequency combination renders the receiving apparatus designed therefor proof 40 against operation by speech currents of the particular frequencies used for ringing for the reason that to operate the biased polarized relay, the currents of these two frequencies must occur sequentially at the proper rate of alternation.

The present invention has as one of its 45 features the adaptation of this alternate frequency ringing system to carrier wave transmission. In carrier wave transmission whether by unguided or by circuit guided waves, there is frequently a tendency for interference to occur. In radio transmission, static energy and other strays cause such interference, particularly in certain latitudes and during certain times of the year, that it 50 has been considered practically impossible 55 to free radio teledynamic operation from in-

terference. In guided wave transmission and particularly in multiplex signaling systems, cross talk from other transmission channels as well as combination frequency currents produced in the signaling channel 60 itself, when external disturbing energy is impressed upon the channel, may cause a false operation of the signal receiving element.

According to the present invention, a carrier wave transmission system is provided at its transmitting station with means to cut off the local talking circuit from the outgoing carrier wave channel and to connect instead to the outgoing channel a source for alternately applying two alternating currents of different frequencies in a regular sequence. These alternately applied currents are caused to modulate the outgoing carrier wave in the same manner that it is 75 modulated by speech currents when carrier wave telephony is in progress. At the receiving station, the modulated carrier wave is detected or demodulated by the same apparatus used for detection of speech modulated 80 waves and the detected alternate frequency currents are caused to energize selective circuits to control the operation of a differentially acting relay which in turn operates the local signal element or applies the ringing signal to the receiving circuits as the case may be. By making the receiving apparatus responsible only to the conjoint action of the predetermined frequencies applied in a predetermined manner, the possibility of false signals being received is remote.

An object of the invention is to provide a carrier wave signaling system which will be free from interference by strays and cross talk signals. A further object of the invention is to provide means for signaling to an operator in systems in which telephone lines are connected to each other by means of carrier wave toll connections.

For an understanding of a system operating according to this invention and embodying its features, reference may be had to the accompanying detailed description taken in connection with the annexed drawing in 105 which Fig. 1 and Fig. 2 together illustrate, diagrammatically, signaling circuits for connecting a low frequency line to a carrier wave transmission circuit and Fig. 3 illustrates a modification of a detail of Fig. 1. 110

In considering the drawing Fig. 2 should be placed at the right of Fig. 1. Referring to these figures, a standard operator's cord circuit 1 is shown associated with a trunk 5 circuit 2 which terminates in carrier wave transmitting channel 3 and carrier wave receiving channel 4. Associated with the trunk circuit 2 is the alternate frequency oscillation source 5 which serves to supply alternating currents of two frequencies in regular sequence to said trunk circuit for transmission, and the alternate frequency receiving apparatus 6, which receives alternate frequency currents incoming over said trunk 10 circuit and responds thereto to give a ring or other signal indication. The principal elements may now be described in detail.

The alternate frequency source 5 consists of a three-element vacuum tube oscillator 7 having alternating current plate and grid circuits coupled in feed back relation by a transformer 8. The frequency of the oscillations produced is determined in well known manner by the tuning of the closed circuit 15 including the primary winding of the transformer 8 and capacity element 9. An additional condenser 10 is arranged to be connected in parallel with element 9 to change the tuning of this circuit and in consequence 20 thereof to change the frequency of the alternating current produced. A three-element vacuum tube amplifier 11 has its grid filament circuit associated with the secondary winding of the transformer 8 and according- 25 111 serves to amplify the oscillations produced by oscillator 7 and to supply the amplified oscillations over a transformer to a circuit 12 adapted to be associated with the trunk circuit 2 by means of a relay 13. The plate battery 14 for the oscillator and 30 amplifier is normally disconnected so that these devices are inactive. A start relay 15 under control of the operator is provided with two left hand contacts, the front one of 35 which is used to connect up the plate battery and the back one of which closes a circuit from ground through a source 16 of ringing alternating current and the biased polarized relay 17 which controls the tuning 40 of the alternate frequency source.

The alternate frequency receiving apparatus 6 comprises a three-element thermionic amplifier 19 connected by a potentiometer 20 to the two series transformers 21 45 and 22, the primary winding of each of which is shunted by an antiresonant circuit tuned to the frequency of one of the alternate frequency currents but having low impedance relative to its shunted transformer 50 winding for current of the other alternate frequency. Transformer 21 serves to impress one of the alternate frequency currents on a relay tube 25 which controls the direct current of the upper winding of differentially acting relay 26 and the transformer 22

is in similar manner related to the lower winding of relay 26. The armature of relay 26 carries a movable contactor engaging at the outer limits of its motion, two stationary contacts 35, through either of which it may 70 complete a circuit from ground through a slow acting relay 36. If the movable contactor is caused to vibrate at the proper frequency, that is, the frequency of alternation of the two alternate frequency currents, the 75 circuit of relay 36 is in effect maintained open to deenergize the relay 36 and release its armature.

The carrier wave transmitting channel 3 may comprise a three-element amplifier 27 of the vacuum tube type to the output circuit of which is connected a constant current modulating system 28. This modulating system for producing and modulating carrier waves is well known and has 85 been described in the paper by Messrs. Craft and Colpitts entitled "Radio Telephony" volume 38, page 360, proceedings of the American Institute of Electrical Engineers. The output circuit of this high frequency 90 modulating system is associated with an antenna for radiating the modulated wave energy to a distant receiving station.

The carrier wave receiving channel 4 comprises a receiving antenna for receiving energy radiated from a distant station, a thermionic detector 29 and a thermionic amplifier 30 connected thereto for transmitting the detected currents to the conductors of trunk 2. The thermionic detecting and amplifying apparatus is of conventional type and needs no further explanation. The carrier wave transmitting and receiving channels, which are conjugately associated with the trunk circuit 2 through the customary hybrid coil arrangement with the usual net N for maintaining the impedance balance, in effect constitute a four-wire circuit connected to the trunk circuit 2. It should be clearly understood that the invention is not limited to radio transmission but that the modulated carrier waves may be guided over a four-wire circuit to the distant station, the four-wire circuit either extending between the local and distant stations or being connected to a two-wire circuit which does so extend.

In the case of radio operation, the transmitting and receiving antennæ of the local station may be physically widely separated and may be tuned to operate at widely different carrier frequencies, it being understood that each operates at the same carrier frequency as its cooperating antenna at the distant station.

The circuit of Fig. 3 illustrates a modified alternate frequency receiving apparatus in which the amplifier 19 and selecting circuits 23 and 24 are replaced by two parallel filters 30' and 31 to each of which an am-

plifier 32 is connected. Each amplifier 32 has associated in tandem therewith a thermionic relay 33 for controlling the direct current in the winding of the differentially 6 acting relay 34 which corresponds to the relay 26 in Fig. 1.

The relationship of the various parts of the system which have been described and the nature and function of the various other 10 elements may be understood from the following description of the mode of operation of the system as a whole.

Assume for example, that a local subscriber desires to communicate with a subscriber 15 associated with a distant exchange, over the carrier transmission channels. When a signal is received over the line circuit of this local subscriber (not shown) the local operator in responding thereto connects 20 with the subscriber's line the cord circuit 1. The operator's monitoring apparatus 40 may be connected with the cord circuit 1 by means of the monitoring key 41. Upon ascertaining that a connection is desired 25 for communication with a subscriber associated at a distant exchange, the operator inserts the plug 42 of the cord circuit 1 into the jack 43 of trunk circuit 2. This completes a circuit from ground through 30 battery over the sleeve contact of the plug, the sleeve of the jack and relay 44 to ground. Relay 44 energizes and remains energized as long as the plug 42 and jack 43 are connected. The left-hand armature of relay 44 is 35 thereby closed on its contact and completes a circuit from ground over the line conductors of a repeating loop of trunk circuit 2, through relay 45 and battery back to ground. Relay 45 energizes and connects up the 40 plate battery 46 of amplifier 27 and the tubes of the constant current modulating system 28, thus rendering each of these tubes active. At the same time, relay 44 pulls up its front right-hand armature contact preparing 45 a circuit for relay 47. The right-hand back armature of relay 44 is also pulled up. The operator thereupon operates a ringing key 48 to connect a source 49 of alternating ringing current to trunk circuit 50. This ringing current traverses a bridge path 51 including relay 51 which is consequently energized and pulls up both its right-hand and left-hand armatures during 55 the application of the ringing current. The left-hand armature of relay 51 closes a local circuit for start relay 15. Relay 15 in energizing closes its front and back armatures on their respective contacts, the front armature connecting plate battery 14 to the tubes 60 7 and 11 of the oscillator and amplifier respectively. The back armature closes a circuit from ground through a 20 cycle alternating current source 16 and the biased polarized relay 17, thus varying the tuning of the oscillator 65 7 by the introduction of condenser 10 at

20 times per second. The oscillator 7 with the condenser 10 disconnected will produce alternating current of one frequency, for example, 550 cycles and with the condenser 10 connected will produce current of another 70 frequency as, for example, 400 cycles. It follows that amplifier 11 will impress upon the circuit 12 a continuous train of oscillations of 400 cycles frequency, followed by a train of 550 cycle oscillations and in turn 75 by another train of 400 cycles, these trains occurring in regular sequence at the rate of 20 trains of each frequency per second. Returning to relay 51, the right-hand armature is closed at the same time as its left-hand 80 armature to complete a circuit for relay 13 which disconnects that portion of the trunk circuit 2 adjacent to cord circuit 1 and connects in its stead circuit 12 to apply the trains of alternate frequency currents to 85 trunk circuit 2 for transmission over its outgoing channel. At the same time, relay 13 operates to disconnect the alternate frequency receiving channel 52 to prevent the transmission of a signal back over the calling 90 subscriber's line. The alternate frequency currents applied to the trunk circuit 2 are transmitted over the hybrid coil through amplifier 27 to the constant current modulating system 28, thereby varying the energy 95 radiated from the transmitting antenna in well known manner.

Since the apparatus at the distant exchange may be similar in every respect to that illustrated in Figs. 1 and 2 the course of 100 the modulated signal energy received at the distant station may be considered by noting the operation of the local station apparatus for receiving modulated energy. A modulated wave incident upon the local receiving 105 antenna, causes modulated currents of corresponding frequency and wave form to be applied to the thermionic detector 29. These currents are detected, and the detected alternate frequency wave trains are applied 110 by means of amplifier 30 and the hybrid coil connection to the trunk circuit 2. In considering receiving conditions, it should be noted that the various relays and circuits are all in normal receiving condition as indicated in Fig. 1, the local cord circuit 1 of the receiving operator being disconnected from the trunk circuit 2. The alternate frequency wave trains received over trunk 2 115 pass to receiving channel 52 and after amplification by amplifier 19 are supplied to transformers 21 and 22 by the potentiometer connection 20. As a result of the high impedance of the antiresonant circuit 23 for the wave train of one of the two frequencies, 120 substantially all the current of that frequency will be forced to traverse the primary winding of the transformer 21. Since the antiresonant circuit 24 is of relatively 125 low impedance compared with its shunted 130

winding of transformer 22 for currents of the frequency under consideration, the currents which traverse the primary winding of transformer winding 21 will be effectively 5 shunted from transformer 22 by the anti-resonant circuit 24. In a similar manner, the waves of the other frequency will be diverted through the primary winding of the transformer 22. It follows that one relay 25 will be caused to respond and change its space current throughout the duration of one of the alternate frequency currents and the other relay 25 will similarly respond throughout the duration of the 10 other frequency wave. The two windings of relay 26 which act differentially upon the armature will alternately attract its armature causing its contactor to vibrate between contacts 35 at a 20 cycle rate, thus maintaining the circuit of relay 36 effectively open. Relay 36 accordingly deenergizes and releases its armature to complete a circuit for relay 54. Relay 54 pulls up its right-hand armature to energize the lamp or other signal 55 and at the same time closes a locking circuit 15 for itself through its left-hand armature and contact.

The operator at the receiving exchange noting this signal, inserts the plug 42 of 30 the local cord circuit into the jack 43 of the trunk circuit 2, thereby energizing local cut-off relay 44 to open its back right-hand armature contact and cut off the signal. At 35 the same time, cut-off relay 44 pulls up its right-hand front armature preparing a circuit for relay 47. It further closes its left-hand armature contact to render active the carrier wave transmitting apparatus of 40 transmitting channel 3 as described in connection with the operation of the calling station. The operator thereupon connects her monitoring apparatus 40 to cord circuit 1. When talking currents are impressed 45 upon the cord circuit 1 they are transmitted over trunk circuit 2 and caused to modulate the carrier wave, the energy of which is thereupon transmitted to the distant calling station. The receiving operator having thereby obtained the necessary information 50 completes the desired connection after first calling the desired subscriber in the usual manner and then connecting the local cord circuit 1 to the line of the desired subscriber. The connections between the two subscribers 55 are now completed and communication proceeds in the usual manner.

Should the calling subscriber desire to 60 recall the called subscriber before the connections at the operators' stations have been broken, he may communicate the fact to the operator at the calling exchange. The operator applies ringing current from ringing source 49 and the alternate frequency waves 65 received at the called exchange cause the deenergization of relay 36 whereby the cir-

cuit previously described through relay 47 is completed causing this relay to energize and connect ringing source 56 to the cord circuit 1. This ringing current energizes local supervisory relay 57 to actuate signal 70 58 in the usual manner and the operator at the called or receiving exchange noting this signal, may thereupon recall the called subscriber. Upon the termination of the 75 conversation as indicated by the lighting of the usual lamps associated with the subscriber's line circuits, each operator may disconnect her cord circuit from the subscriber's line and from trunk 2 thereby restoring the various circuits to normal condition. 80

The operation of the arrangement of Fig. 3 is substantially the same as the operation of receiving apparatus 6 of Fig. 1. Alternate frequency wave trains are received over 85 channel 52. Filter 30' passes only the wave train of one alternate frequency and filter 31 passes only the wave train of the other alternate frequency. The amplifiers 32 and thermionic relays 33 operate in the ordinary manner to actuate relay 34. The operation of relay 34 will be understood from the description of the operation of relay 26. An obvious adaptation of this apparatus 90 for code signaling may be made by using the same method to operate the slow release relay at the receiver, the operation of this relay indicating the desired signal to the operator at the receiving station. It is obvious that this invention may be applied to teledynamic operation generally. Although the invention has been described in connection with a specific transmission circuit, it is to be understood that it is not to be limited thereto, but only by the scope of 95 the appended claims. 100

What is claimed is:

1. A method of carrier wave transmission which comprises modulating a carrier wave by means of a plurality of successively recurring waves of different frequencies to 110 constitute a single signal element.

2. A method of selective transmission which comprises transmitting a carrier wave modulated by alternately recurring equal duration trains of two different frequencies to 115 constitute a single signal element.

3. A method of signaling by carrier waves which comprises modulating a carrier wave by a plurality of waves of different frequencies successively recurring to constitute a 120 single signal element.

4. A method of signaling by carrier waves which comprises modulating a carrier wave by two waves of different frequencies alternately repeated to constitute a single signal element. 125

5. A method of signaling by carrier waves which comprises modulating a carrier wave by a plurality of waves of different frequencies 130

- cies successively recurring, deriving the wave components of different frequencies from the carrier wave and controlling an indicator by the joint action of the derived 5 wave components.
6. A method of signaling by carrier waves which comprises causing a source of current to supply alternately recurring waves of different frequencies, modulating a carrier 10 wave by said alternating recurrent waves, deriving the alternately recurring waves from the carrier wave and controlling an indicator by the joint action of said derived waves.
- 15 7. A method which comprises transmitting a carrier wave modulated by successively recurring currents of different frequencies, deriving the currents of different frequencies from the carrier wave and operating a controlled device by the cooperative action of the energies of said derived currents.
- 20 8. A method which comprises transmitting a carrier wave modulated by successive waves of different frequencies recurring at a definite frequency, deriving the waves of different frequencies from the carrier wave and controlling a device by the derived waves of said frequencies recurring at 25 said definite frequency.
- 25 9. A carrier wave system comprising means to supply a wave train composed of a plurality of waves of different frequencies succeeding each other at a definite rate to 30 constitute a single signal element and means for modulating a carrier wave by said train.
- 35 10. A carrier wave system comprising a carrier wave channel, means to control a source of energy to supply waves of different frequencies, and means for impressing 40 said waves successively upon said channel at a definite rate to modify a carrier wave several times alternately by said waves to produce a single signal element.
- 45 11. A carrier signaling system comprising means for modulating a carrier wave by two wave trains applied alternately in regular sequence to constitute a single signal element.
- 50 12. A carrier wave system comprising means for deriving from an incoming carrier wave non-simultaneous wave trains occurring in regular sequence and means for controlling a responsive device by the joint action of said derived wave trains.
- 55 13. In combination, a modulating element, a source of carrier waves, a source of alternately recurring wave trains of two different frequencies to constitute a single signal element and means for causing said wave trains to operate upon said modulating element to modulate said carrier waves.
- 60 14. A signaling system comprising a carrier wave circuit, a low frequency circuit, said carrier wave circuit comprising means 65 for detecting carrier waves received thereover to derive alternately recurring wave trains of different frequencies and means responsive to said alternately occurring detected wave trains to operate a signal associated with said low frequency circuit. 70
15. A carrier wave transmission system comprising a source of carrier waves, a normally inactive source of signaling waves, and a ringing key to simultaneously render 75 said inactive source active and to associate it with said carrier wave source to modulate said carrier waves in accordance with said signaling waves.
16. A receiving circuit, means for impressing thereon currents of two different frequencies, two translating elements adapted to respond to currents of said different frequencies respectively, and means for connecting said elements to said circuit comprising two transformers having their primary windings in series and having each primary winding shunted by a closed loop circuit tuned to the frequency of the current to be transmitted by its shunted winding. 80 85 90
17. A carrier wave system comprising an operator's station, a cord circuit thereat, a carrier wave transmission channel having an inactive source of carrier waves, and means responsive to connection of said cord circuit to said transmission channel at said operator's station to automatically cause said carrier wave source to become active. 95
18. A radio system comprising a transmitting channel, an oscillator of the electron relay type connected thereto and having its space current source normally disconnected, an operator's cord circuit, and means responsive to connection of said cord circuit to said channel to connect said space current source to render said oscillator active. 100 105
19. In a signaling system, means for transmitting a carrier wave, means for modulating said wave at a plurality of frequencies in cyclic order at a definite 110 periodicity of cyclic recurrence in combination with a receiver selectively responsive to the carrier frequency, each of the plurality of frequencies, and the frequency of cyclic recurrence.
20. In a distant control system, means for transmitting periodic energy, means for varying said energy at a plurality of different frequencies in cyclic order at a definite periodicity of cyclic recurrence in combination with a controlled element responsive only when the energy variation is at the definite periodicity of cyclic recurrence. 115 120
21. A signal transmission system comprising means for producing and radiating an unmodulated high frequency carrier wave during non-signaling intervals, means for producing a plurality of lower frequency waves, and means for modulating said high frequency wave in regular periodic order 125 130

with said lower frequency waves during signaling intervals.

22. A signal transmission system comprising means for producing a carrier wave, a 5 ringing key, and means actuated by the actuation of said key to vary said carrier wave in cyclic order in accordance with a plurality of modulating frequencies.

23. In a system for controlling a distant 10 element, means for transmitting carrier wave energy varied at two frequencies in alternation at a definite rate of alternation in combination with selective means whereby the distant element to be controlled is 15 affected in the desired manner only when the carrier wave energy, both of the frequencies,

and the rate of alternation correspond to certain selective characteristics of said selective means.

24. A selective receiver adapted for control by energy varied in accordance with two waves of definite frequencies recurring alternately at a definite periodicity comprising means selective to the frequency of the energy, means selective to the frequency of 25 each of the waves, and means selective to the periodicity of alternation.

In witness whereof, I hereunto subscribe my name this 24th day of August, A. D., 1920.

PAUL B. MURPHY.
